Attorney.

UNITED STATES PATENT OFFICE.

CHARLES ROSSIGNOL, OF PARIS, FRANCE.

PERMUTATION-LOCK FOR TOY SAFES.

SPECIFICATION forming part of Letters Patent No. 625,203, dated May 16, 1899.

Application filed May 4, 1898. Serial No. 679,670. (No model.)

To all whom it may concern.

Be it known that I, CHARLES ROSSIGNOL, manufacturer, a resident of 71 Boulevard Voltaire, Paris, France, have invented new and useful Improvements in Permutation-Locks for Toy Safes, (for which an application for patent has been filed in France, dated October 13, 1897, No. 271,269, and in Great Britain, dated April 16, 1898, No. 8,926,) of which the following is a full, clear, and exact description.

This invention relates to toy safes, and has for its object a permutation-lock for such safes that will operate in an efficient manner and be of simple construction.

The invention consists in certain details of construction and arrangement of the parts, which I shall first describe and then point out the novel features in the appended claims.

In the accompanying drawings, Figure 1 represents a front elevation of the cabinet-safe, and Fig. 2 a horizontal section on a line above the fastening. Figs. 3 and 4 are inside face and edge views, respectively, of the door. Fig. 5 is an inside elevation, and Fig. 6 a section of the lock mechanism seen from below. Figs. 7 to 10 show separately the details of the lock mechanism.

As will be seen from the drawings, the toy is a reproduction of an ordinary metal cabinet-safe on a small scale, this imitation being obtained by constructing the body of the safe of plates of zinc, tin-plate, or other thin metal suitably shaped and stamped with moldings and connected together by soldering or otherwise, while the decorative columns are metal tubes having capitals and plinths of lead or other fusible metal cast in a mold. Upon the door, which is a strong metal plate, is mounted the fastening mechanism, which comprises a sliding bolt A, which when shot passes into the locked position in rear of the rabbet B of the door-frame, against which the door C closes. The bolt A is guided at its front end in the bolt-casing D, which is stamped out of sheet metal and through which the bolt slides in the manner of an ordinary lock, the bolt being operated by means of knobs E, which are rotatably mounted on it and are adapted to slide in elongated slots e in the door C when the bolt is retracted. The door is hinged at c and is opened by pulling on one or other of the knobs E after the bolt A has

been slid back, this, however, only being possible when each of the knobs E has been previously rotated to a certain angular position indicated by a particular letter, figure, or other sign exhibited on a disk. To this end each knob, of which there may be any desired number, two being shown in the drawings, carries a disk G, Fig. 10, bearing letters, figures, or other signs, and a ratchet-wheel H, both fixed to knob E, so as to turn therewith. The rear boss h of each ratchet-wheel H projects through a slot in the casing D and is provided with a lateral notch h', which when caused to register with a tongue d lying in said slot permits of the knob-piece being moved in a direction to retract the bolt, such movement being otherwise prevented by the tongue d lying in the path of the boss h. The plate I, which is apertured to correspond to the holes in the bolt A, assists to retain the ratchets H H at the proper distance apart.

To draw back the bolt, it is first necessary to rotate each knob E to bring the notch h' of its ratchet opposite the corresponding tongue d, the correct position of each notch being (when attained) shown by the predetermined letter or figure on each disk appearing at an aperture f in door C. A flat spring a, abutting against the casing D, maintains the bolt in the "shot" position, so that the door will lock itself when closed without the necessity of altering the disks G from their open position.

r r are two flat springs which serve as pawls for retaining the ratchets H in any position in which they may be set. The springs r r and a are each formed with an offset a', Fig. 8, which offsets are received in slots in bolt A, whereby the springs are retained when bent without the means of fixing, they being prevented from slipping out of the slots by the casing D. The parts G H E are united as one by providing each ratchet H with a threaded shank on which the knob E screws, the knob thus serving as a nut for clamping the letter-disk G to the ratchet H, and in order to change the combination of letters or figures it is simply necessary to unscrew the knobs E, so as to allow of turning the disks G.

When the disks G are placed on the inside of the door C, the latter is provided with apertures f for exhibiting a letter or figure on

said disks. If the disks are placed on the outside of the door, a pointer would be provided, under which the face of each of said disks would move.

5 The above-described mode of constructing the fastening presents this peculiarity that all the parts of the mechanism are fitted in place and retained without the aid of solder or rivets, the casing D alone being fixed to the 10 door C by screws or other means. The mechanism can thus be easily fitted in place and dismounted for the purpose of regulating the action when the safe is in course of manufacture.

15 I claim—

1. In a toy safe, the lock consisting of a casing formed with an elongated opening in its rear face and a tongue on said rear face and extending into said opening, a bolt in 20 said casing and provided with an opening, and a shank in said casing and having one end inserted through the opening in said bolt and through the outer face of the casing, the other end of said shank being formed with a 25 notched boss fitted to slide in the elongated opening in the rear face of the casing, the notch of said boss being arranged to register with the said tongue whereby to permit the sliding of the boss and the withdrawal of the 30 bolt, as and for the purpose set forth.

2. A keyless fastening for a toy cabinet-safe, consisting of a bolt A supported in the door and lock casing and carrying screw-threaded knobs E, ratchets H provided with

35 screw-threaded shanks and notched bosses h, lettered or figured disks G, and springs r in combination with tongues d adapted to prevent retraction of the bolt unless the notches h register with said tongues, as specified.

40 3. In a toy safe, the lock consisting of a casing formed of sheet metal with an elongated slot in its rear face and a tongue extending into said slot, a bolt in said casing, a shank fitted in said bolt and inserted through

45 the said elongated opening, at which point it is provided with a notched boss fitted to slide in said opening, the notch being arranged to be brought to register with the tongue on the rear face of the casing when the shank is

turned, whereby to permit the sliding of said 50 boss and shank, and means for turning and sliding said shank, as and for the purpose set forth.

4 In a toy safe, the combination of a lock-casing, a bolt mounted therein, a shank secured to said bolt and inserted through an elongated slot in the casing, the said shank being fitted to rotate and provided with a notched boss adapted to register with a tongue when the shank is rotated whereby to permit 60 of sliding the shank and bolt, a character-bearing disk rotatably fitted on said shank, and a knob on said shank, the said knob clamping said disk thereon and preventing the disk from being rotated when so clamped 65 whereby the loosening of the knob will permit of the adjustment of the disk, as set forth.

5 In a toy safe, a lock consisting of a casing, a bolt therein, a shank fitted to rotate in said bolt and having one end inserted through 70 an elongated slot in the casing, a spring-pressed ratchet-wheel secured on said shank, a notched boss on said shank and arranged to register with a tongue whereby to permit of the sliding of the shank, a character-bearing 75 disk provided with a central circular aperture by which it is loosely inserted on said shank, and a knob screwing on the end of said shank outside the lock-casing, and by which the parts are clamped together, turned, 80 and slid, the partial unscrewing of said knob permitting the disk to be rotated on the shank, as and for the purpose set forth.

6 In a toy safe, the combination of the lock-casing, the bolt therein, the shank inserted 85 through said bolt, the adjustable character-bearing disk formed with a circular aperture by which it is mounted to turn on said shank, the locking and unlocking devices for said bolt, and the knob for operating such devices, 90 said knob clamping the disk on the shank whereby to prevent its turning thereon after it has been adjusted by turning as set forth.

CHARLES ROSSIGNOL.

In presence of—

EMIL CERVELIEUS,

VALENTIN NEUMEGEN.
